(57) **CLAIM**

The ornamental design for a magnetic holder with magnifying lens for viewing a pressed penny, substantially as shown and described.

DESCRIPTION

FIG. 1 is a front upper perspective view of the magnetic holder with magnifying lens showing my new design;

FIG. 2 is a front lower perspective view of the magnetic holder with magnifying lens;

FIG. 3 is a right side view of the magnetic holder with magnifying lens;

FIG. 4 is a left side view of the magnetic holder with magnifying lens;

FIG. 5 is front view of the magnetic holder with magnifying lens;

FIG. 6 is a rear view of the magnetic holder with magnifying lens;

FIG. 7 is a top view of the magnetic holder with magnifying lens;

FIG. 8 is a bottom view of the magnetic holder with magnifying lens;

FIG. 9 is a front upper perspective view of the magnifying lens separated from the magnetic holder; and,

FIG. 10 is a front lower perspective view of a magnet separated from the magnetic holder.
